UNITED STATES PATENT OFFICE.

HERMAN TORLUEMKE, OF ST. LOUIS, MISSOURI.

TOY.

1,042,294.

Specification of Letters Patent. Patented Oct. 22, 1912.

Application filed May 4, 1912. Serial No. 695,265.

To all whom it may concern:

Be it known that I, HERMAN TORLUEMKE, a citizen of the United States, residing at St. Louis, State of Missouri, have invented 5 certain new and useful Improvements in Toys, of which the following is a specification, reference being had to the accompanying drawings.

This invention relates to new and useful 10 improvements in toys and more particularly to that class known as figure wheeled toys, the object of this invention being to provide a figure wheeled toy which is provided with novel propelling mechanism for toys of this 15 character.

Another object of the invention is to provide a toy of this character which will possess advantages in points of efficiency and durability, be inexpensive to manufacture 20 and at the same time simple in construction and operation.

With the above and other objects in view, the invention consists in the novel features 25 of construction and the combination and arrangement of parts hereinafter more fully described, pointed out in the claims, and shown in the accompanying drawings in which,

Figure 1 is a side elevation of a toy constructed in accordance with my invention. Fig. 2 is a top plan view. Fig. 3 is a sectional view on the line 3—3 of Fig. 1. Fig. 4 is an interior view of the motor casing showing the arrangement of the operating 35 parts contained in one of the chambers thereof. Fig. 5 is a sectional view of the line 5—5 of Fig. 4. Fig. 6 is a detail sectional view showing the means of connection between the plate and the front fork of the 40 frame.

Referring more particularly to the drawings, 1 indicates the body of the figure which is preferably constructed of steel, aluminum or other similar material. Formed 45 integral with the body and extending downwardly from the lower end thereof and arranged in laterally spaced relation to each other are lugs 2 arranged in pairs at the front and rear of the figure as shown at 3 and 4, said lugs being arranged upon each side of the body plate 5 of the frame of the toy and securely held in place by means of the rivets 6. Formed integral with the body plate 5 and extending outwardly at one end thereof, is a sleeve 7 which is adapted to be arranged within the slot 8 formed in the

body portion 9 of the front fork of the frame, said sleeve being held securely in place by means of the screw 10 passing through the sleeve 7 and having its threaded 60 end screwed into the body portion of the fork. Arranged transversely through the body plate 5 is a pivot rod 11, the outer ends of said rod being bent upwardly at right angles as shown at 12. Pivotedly mounted at 65 one of their ends upon the rod 11 and arranged upon each side of the body plate are the links 13 which form the upper limb of the figure, the other ends of said links being pivotally secured to the upper ends of the 70 links 14 which form the lower limb of the figure. Formed integral with the feet 15 of the figure are the castings 16 having openings 17 formed therein, said castings being secured to the cranks 18 by means of the 75 screws 19 passing through the castings and threaded into the outer end of the cranks. The cranks 18 are secured upon opposite ends of the axle 20 so that as the wheel 21 revolves it will actuate the limbs of the 80 figure.

Formed integral with the body plate 5 and extending downwardly and rearwardly therefrom are the diverging arms 22, the rear ends of which are bent to form a 85 straight portion 23. The straight portion of one of the arms 22 is substantially circular in form and provided upon its periphery with a plurality of ears 24 which are adapted to register with the ears 25 formed on the motor casing 26 to securely fasten the circular end of the arm to one side of the casing. Thus it will be seen that the circular end of the arm forms a plate adapted to close one side of the casing. 95

The casing 26 is provided with two chambers 27 and 28, the chamber 27 being circular in form and adapted to receive the helical spring 29, one end of which is secured to the transverse shaft 30 and the other end secured to the inner wall of the chamber 27. The chamber 28 at one end is substantially circular in form as shown at 31 and adapted to receive the gear wheel 32, which is keyed to the shaft 30 and adapted to rotate therewith. The other end of the chamber 28 is substantially oval in form as shown at 33 and is adapted to receive the pinion 34, which meshes with the gear wheel 32, said pinion being formed integral with a second gear 35 which meshes with a second pinion 36 mounted upon the end of the axle 100 105 110

37, the other end of the axle 37 being mounted in the rear end of the rim opposite the motor casing. The outer end of the shaft 30 extends outwardly beyond the casing 26 5 and a wheel 38 is mounted thereon, the extreme end of said shaft being threaded and having a winged-nut 39 secured thereon so that the shaft 30 can be rotated to wind the spring 29, the tension of the spring rotating the axle 37 which in turn will rotate the wheel 40 mounted upon the outer end thereof. Thus it will be seen that motion will be imparted to all of the wheels of the toy through the medium of the wheel 40.

15 From the foregoing description in connection with the accompanying drawing it will be readily seen that after the spring 29 has been tightly wound up, and the toy placed upon a level surface, the tension of 20 the spring will tend to rotate the axle 37 which in turn will rotate the wheel 40 and impart motion to the toy.

While I have shown and described the preferred form of my invention it will be 25 obvious that various changes in the details of construction and in the proportions may be resorted to for successfully carrying my invention into practice without sacrificing any of the novel features or departing from 30 the scope thereof as defined in the appended claims.

What I claim is:

1. In a device of the character described, the combination of a frame comprising a 35 body plate, a sleeve formed integral with said body plate and extending outwardly at one end thereof, a fork comprising a body portion, having a slot formed therein in which said sleeve is arranged, and a screw 40 passing through the body portion of the fork and through the sleeve, and having its threaded end screwed into the body portion of the fork at the lower end of the slot to 45 pivotally secure the fork to one end of the frame.

2. In a device of the character described, the combination of a frame comprising a body plate, a figure rigidly secured to the 50 upper edge thereof, a wheel pivotally secured to the body plate at one end thereof, diverging arms formed integral with the other end of the plate, a motor casing secured to the outer end of one of said arms, a shaft mounted in said casing and extending 55 outwardly through the end of the arm, a wheel mounted on the outer end of the shaft, an axle having one end mounted in

the casing, and its other end mounted in the outer end of the other of said arms, a wheel mounted upon the outer end of the 60 axle, and means arranged within said casing and operatively connected with one end of said axle to impart motion to the same which in turn will rotate the wheel to propel the frame. 65

3. In a device of the character described, the combination of a frame comprising a body plate, a sleeve formed integral at one end thereof, a fork comprising a body portion having a slot formed therein in which 70 said sleeve is arranged, a screw passing through the body of the fork and through the sleeve and having its threaded end secured into the body portion of the fork at the lower end of the slot, an axle mounted 75 in the outer ends of the fork, a wheel mounted upon the axle and arranged within the fork, a crank secured to each end of the axle, a casting loosely secured to the outer ends of 80 said crank, a transverse pivot rod mounted in the body plate, links having one of their ends pivotally mounted upon said rod and arranged upon opposite sides of the body plate, and links having one of their ends pivotally connected to the other ends 85 of the levers, and their other ends formed integral with the castings.

4. In a device of the character described, the combination of a frame comprising a 90 body plate, a sleeve formed integral with said body plate and extending outwardly at one end thereof, a fork comprising a body portion having a slot formed therein, in which said sleeve is arranged, a screw passing through the body portion of the fork 95 and through the sleeve and having its threaded end screwed into the body portion of the fork at the lower end of the slot to pivotally secure the fork to one end of the frame, a figure comprising a body having 100 spaced ears formed thereon at diametrically opposite points and arranged in pairs at both ends of the body, said ears being disposed upon each side of the body plate, and rivets passing through the slots and through 105 the body plate to rigidly secure the body of the figure upon the frame.

In testimony whereof I hereunto affix my signature in the presence of two witnesses.

HERMAN TORLUEMKE.
